(57) **CLAIM**

The ornamental design for a pacifier shield cover, as shown and described.

DESCRIPTION

FIG. 1 is a front elevation view of a pacifier shield cover showing my new design;

FIG. 2 is a rear elevation view thereof;

FIG. 3 is a right elevation view thereof, the opposite side being a mirror image of the shown;

FIG. 4 is a top plan view thereof;

FIG. 5 is a bottom plan view thereof; and,

FIG. 6 is an isometric view thereof.

The broken lines in FIG. 6 depict a pacifier as environmental subject matter only and form no part of the claimed design.
